UNITED STATES PATENT OFFICE.

ERASTUS E. WINKLEY, OF LYNN, MASSACHUSETTS.

SOLE-LEVELING MACHINE.

SPECIFICATION forming part of Letters Patent No. 644,654, dated March 6, 1900.

Application filed June 15, 1899. Serial No. 720,694. (No model.)

To all whom it may concern:

Be it known that I, ERASTUS E. WINKLEY, a citizen of the United States, residing at Lynn, in the county of Essex and State of Massachusetts, have invented certain new and useful Improvements in Sole - Leveling Machines; and I do hereby declare the following to be a full, clear, and exact description of the invention, such as will enable others skilled in the art to which it appertains to make and use the same.

The present invention relates to sole leveling or beating-out machines of the type disclosed in Letters Patent of the United States No. 555,548, of March 3, 1896. In the machine of said patent there are embodied a shoe-supporting jack and a sole-leveling roll actuated by automatically-operating connected mechanism, whereby the relative longitudinal position and lateral inclination of the roll and jack are caused to change during the operation of leveling the sole and all the parts of the shoe-sole brought under the action of the roll and properly leveled and conformed to the contour of the bottom of the last.

The roller type of machine has been found generally satisfactory in use; but in some classes of work it is deemed desirable to subject the sole to a hammering or beating-out action; and it is therefore the object of the present invention to produce a machine of the type mentioned which shall embody a sole-leveling hammer arranged to deliver rapid sharp blows to the sole, to level the same and conform it to the contour of the bottom of the last, and to so actuate the jack and hammer that the blows delivered by the hammer shall be at all times substantially perpendicular to the part of the irregular surface of the sole at which it shall at any given time be operating.

To the above end the present invention consists of the devices and combinations of devices, which will be hereinafter described and claimed.

In the accompanying drawings I have illustrated the present invention as being embodied in the machine described in the patent hereinbefore mentioned, in which are disclosed two separate sole-leveling mechanisms actuated by connected mechanism to properly actuate one jack and its coöperating sole-lev-

eling instrumentalities to level a left shoe and the other to level a right shoe, and such is the preferred form of the present invention; but it is in no way limited to such a construction.

In the drawings, Figure 1 shows inside elevation a sole-leveling machine embodying the present invention, a portion of the frame being broken out to show underlying parts. Fig. 2 shows a top plan view with the jacks and their operating mechanism removed. Fig. 3 shows a front view of one of the sole-leveling hammers and parts of its actuating mechanism. Fig. 4 shows a section on line xx , Fig. 3. Fig. 5 shows a broken side elevation of the rear end of the hammer supporting a frame and parts of the hammer-actuating mechanism. Fig. 6 shows a plan view of the same mechanism. Fig. 7 shows a section on line yy , Fig. 6.

Similar reference characters will be employed throughout the specification and drawings to designate corresponding parts.

In the drawings, 1 represents the main frame, of suitable size and shape to support the working parts and substantially the same as the frame in the patent hereinbefore referred to. The jacks 2 may be of any usual or preferred construction, and, as in the patented machine, they are fulcrumed upon a shaft 3, mounted in suitable bearings in the frame 1. Each jack is oscillated about its fulcrum by means of a lever 4, which is fulcrumed on a shaft 5 and pivotally connected to a link 6, which in turn is pivotally connected to an arm 7, extending from the shaft 3, the lever 4 carrying a cam-roll (not shown) which engages a cam-path 8 on the side of the disk or wheel 9. The disk or wheel 9 is mounted upon a shaft 10, having suitable bearings in the frame 1, and is rotated by means of a worm 11, carried by a shaft 12, mounted in bearings in the frame 1, which worm engages a worm-gear (not shown) on the disk or wheel. The shaft 12 is driven from the power-shaft 13 by means of a gear 14, mounted on said shaft, engaging a gear 15 on the power-shaft, the power-shaft carrying suitable pulleys 16, driven by a belt from any suitable source of power.

The foregoing arrangement is substantially the same as in the patent hereinbefore referred to, and in operation the rotation of the

disk or wheel 9 will impart to the jacks 2 oscillating movements to carry the sole of the shoe which may be on the jack longitudinally beneath the sole - hammering mechanism, 5 which will be hereinafter described.

Coöperating with each jack is a sole-leveling hammer, which is rapidly reciprocated toward and from the sole of the shoe to subject the sole to short, sharp, and quick blows as 10 the shoe and jack pass beneath the same, and as it is necessary that the blows of the hammer be delivered on the sole in a line substantially perpendicular to the surface of the sole at all points of the irregular contour of the 15 sole I have provided means for automatically adjusting the relative lateral and longitudinal inclination of the jack and hammer, and in the machine of the drawings this relative adjustment is secured by mounting the 20 hammer in a carrier which is capable of being tipped both longitudinally and laterally about a point substantially at the face of the hammer.

Each hammer 16 is secured to a cross-head 25 17, mounted to reciprocate in guides 18, formed in vertical uprights 19, carried by the oscillating head 20. The cross-head 17 is connected to a block 21 (which also reciprocates in the guide 18) by means of a bolt 22, which 30 passes loosely through bearings 23 in the block 21 and cross-head 17, and said bolt is surrounded by a coiled spring S, interposed between the cross-head 17 and block 21, whereby the blows of the hammer are cushioned. 35

Any suitable means may be provided for actuating the hammer, that shown in the drawings comprising a shaft 24, mounted in suitable bearings 25, carried by the vertical 40 uprights 19, which shaft carries eccentrics 251, engaged by eccentric-straps 26, carried by links 27, pivotally connected to the block 21. Upon one end of the shaft 24 is a pulley 27^x, over which passes a belt or cord 28, which 45 is driven from a pulley 29, mounted to turn on a shaft 30, secured in suitable bearings at the side of the head 20. The pulley 29 is formed integrally with or connected with another pulley 301, which is driven by a belt or 50 cord 31, which passes around idle pulleys 32, mounted on a vertical shaft 33 at the side of the oscillating head 20, thence under and through an opening 34 in said head, and around a pulley 35, mounted on a stud 36 in the head 55 20. (See dotted lines, Fig. 2.) Attached to or formed integrally with the pulley 35 is a pulley 361, which is driven by a belt or cord 37, which passes out of the opening 34 and beneath the head 20 and thence around idle 60 pulleys 38, carried by a vertical shaft 39, secured in a bearing carried by an arm 40, projected from the frame 41, and thence over a pulley 42, mounted on a stud 43, which pulley is formed integrally with or connected to a belt-pulley 44, driven by a belt 441 from the 65 pulley 45 on the shaft 13.

The above arrangement is such that a ro-

tation of shaft 13 will rotate pulley 45 and by means of the belt 441 rotate pulleys 44 and 42, which in turn, through the belt or cord 37 and pulleys 361 and 35 and belt or cord 31 and pulleys 301 and 29 and belt or cord 28 and pulley 27^x, rotate the shaft 24, which by means of the eccentrics 25 and straps 26 imparts rapid reciprocations to the hammer 16, 75 which as the jack and shoe thereon are oscillated, as hereinbefore described, will deliver short, sharp, and quick blows to the sole of the shoe. The bottom of the shoe-sole is of an irregular curved contour, it being curved 80 slightly at the shank and fore part transversely or laterally from side to side of the shoe and from toe to heel. The line is in the nature of a compound curve, it being convex at the fore part and more or less concave at 85 the shank and some parts of the surface are higher than others, and as the work progresses over the surface of the sole the hammer must be raised and lowered accordingly, as a high or low part of the sole is beneath 90 the same and tilted laterally to accommodate itself to the lateral curvature of the sole and longitudinally to accommodate itself to the longitudinal curvature of the sole.

In the present machine suitable mechanism 95 has been provided to automatically raise and lower the hammer and to tilt the same both laterally and longitudinally in proper time relation to the movements of the jack and the particular portion of the shoe-sole which 100 at any time may be under the hammer, the relative tilting movements of the hammer and jack being for the purpose of causing the blows of the hammer to be delivered in a line substantially perpendicular to the surface of the 105 sole, as hereinbefore described.

The lateral tilting of the hammer in the machine of the drawings is obtained by mounting the head 20 on a tubular shaft 46, which is mounted to turn in a tubular bearing 47 of the frame 41, which frame is pivoted at 48 in suitable bearings to the frame of the machine to permit the hammer to be raised and lowered toward and from the sole of the shoe, as will be hereinafter described. 115

To the rear end of each of the tubular shafts 46 is secured an arm 49, carrying a segment 50, (see dotted lines, Fig. 1,) which engages horizontally-reciprocating rack-bars, which are reciprocated in opposite directions by 120 means substantially like the machine of the patent hereinbefore referred to and which need not be herein described, it being understood that one head and hammer will be rocked laterally to level a left shoe and the other to 125 level a right shoe, substantially in the same hammer as the leveling-rolls of the patented machine are actuated.

The rise and fall of the frame 41 is accomplished in the machine of the drawings by 130 means of a link 51, which is pivotally connected thereto and to a block 52, which is adjustably mounted in a slotted arm 53 of a bell-crank lever 54, pivoted at 55 to the frame 1

and having an arm 56 engaging the periphery of a cam 57, mounted on the shaft 10.

The longitudinal tilting movement of the hammer is secured in the machine of the drawings by pivotally mounting the vertical uprights 19 on the studs 30 and 300, carried by the head 20, so that they may tip forward and back in a longitudinal direction. This tilting of the uprights 19 is accomplished by means of a link 58, which is pivotally connected at 59 to a cross-girth 591, connecting the uprights 19 at the back, and to a horizontally-reciprocating rod 60, movable in bearings 61, carried by the head 20, which rod carries at its rear end suitable stop-nuts 62, between which is received a forked arm 63, carried by a rod 64, which is reciprocated in suitable bearings 65, carried by the frame 41, the rear end of said rod 64 being pivotally connected to the upper end of a lever 66, passing through an aperture 67 in frame 41 and mounted on a rock-shaft 68, journaled in suitable bearings in the frame 1. An arm 68 is fixedly secured to the rock-shaft 68 and connected to a link 69, which in turn is pivotally connected to a block 70, adjustable along the slotted arm 71 of a lever 72, fulcrumed at 55 to the frame 1, the lower arm of which carries a cam-roll 73, which engages a cam-path 74, formed in the cam 57.

It is deemed desirable that the hammer 16 be formed with two hammering-faces, such as a comparatively-flat face 75 and a rounded face 76, the flat face being employed when operating on the fore part of the shoe and the rounded face being employed when operating upon the shank of the shoe, and in the machine of the drawings I have provided means for automatically bringing the faces of the hammer into operative position at the proper times, according to the part of the shoe-sole which may be under the hammer at any particular time. To accomplish this result, the hammer 16 is fixedly secured to a shaft 77, which is mounted to rock in bearings 78 in the cross-head 17, one end of said shaft being projected laterally through an opening 79, formed in one of the uprights 19 and carrying an arm 80, which is pivotally engaged by a link 81, which in turn is pivoted to a reciprocating rod 82, passing through the tubular shaft 46 and being pivotally connected at its rear end to a lever 821, which engages said rod through openings 83 and 84, formed in the tubular bearing 47 of frame 41 and in the tubular shaft 46, the said lever being fixedly secured to a rock-shaft 85, which carries an arm 851, pivotally connected to a link 86, which is pivotally connected to a lever 87, fulcrumed at 88 to the frame 1 and carrying a cam-roll (see dotted lines, Fig. 1) engaging a cam-path 89, formed in the cam 57.

Like the machine of the patent hereinbefore referred to, the present machine may be provided with suitable start-and-stop mechanism and means for adjusting the extent of the vari-

ous movements of the jack and the lateral and longitudinal inclination of the hammer. Also it is preferably provided with means under the control of the operator, such as the sliding clutch-rod 161, actuated by a treadle 162 and controlling the clutch 163, which may be by such clutch-rod engaged with the clutch on the collar of the gear 14 to turn the shaft 12 or disengaged therefrom to stop the turning of the shaft 12, whereby to stop the relative longitudinal movements of the jack and hammer to cause the action of the hammer to be prolonged at any point in the sole desired, all of which in the illustrated machine are substantially the same as in the machine of the patent.

In the illustrated embodiment of the present invention I have represented the same as being embodied in a duplex machine—that is, a machine comprising a plurality of shoe-supporting jacks and a sole-leveling hammer coöperating with each jack—and it will be necessary in the operation of this machine one jack and its coöperating hammer will be actuated to level a left shoe, and the other jack and its coöperating hammer will be actuated to level a right shoe, the several cams being formed and arranged to impart to the respective jacks and hammers their relative movements timed and arranged to produce the desired operation of the hammers at any particular point in the shoe-sole which may be at any time under the hammer. It is to be understood, however, that the present invention is not in any sense limited to its embodiment in a duplex machine nor to the details of construction and arrangement which have been particularly illustrated and described.

The operation of the machine itself has been sufficiently described in connection with the foregoing description of its construction and arrangement, and a further description thereof is deemed unnecessary.

Having described the construction and mode of operation of my invention, I claim as new and desire to secure by Letters Patent of the United States—

1. In a sole-leveling machine, the combination with a sole-leveling hammer, of a shoe-supporting jack and connected mechanisms operating automatically to change the relative longitudinal position and lateral inclination of the hammer and jack, substantially as described.

2. In a sole-leveling machine, the combination with a sole-leveling hammer, of a shoe-supporting jack and connected mechanisms operating automatically to change the relative longitudinal position and longitudinal inclination of the hammer and jack, substantially as described.

3. In a sole-leveling machine, the combination with a sole-leveling hammer, of a shoe-supporting jack and connected mechanisms operating automatically to change the rela-

tive longitudinal position and lateral and longitudinal inclination of the hammer and jack, substantially as described.

4. In a sole-leveling machine, the combination with a shoe-supporting jack, of a sole-leveling hammer and mechanism for automatically tilting the hammer both longitudinally and laterally, substantially as described.

10 5. In a sole-leveling machine, the combination with a shoe-supporting jack and a sole-leveling hammer, of connected mechanisms for changing the relative longitudinal position of the jack and hammer, and mechanism 15 for raising and lowering the hammer to accommodate it to the variations in height of the shoe-sole, substantially as described.

6. In a sole-leveling machine, the combination with a plurality of shoe-supporting 20 jacks, of a sole-leveling hammer coöperating with each jack and connected mechanisms operating automatically to actuate one jack and hammer for leveling a left shoe and to actuate the other jack and hammer for leveling a right shoe, substantially as described.

25 7. In a sole-leveling machine, the combination with a shoe-supporting jack, of a sole-

leveling hammer provided with a hammering-face to act upon the fore part of the sole, and a hammering-face to act upon the shank of a 30 shoe-sole, and connected mechanisms operating automatically to actuate the jack and hammer to change their relative longitudinal positions and to bring into operative position either of the operating-faces of the hammer 35 according as the fore part or shank of the shoe is brought into position to receive the blows thereof, substantially as described.

8. In a sole-leveling machine, the combination with a sole-leveling hammer, of a shoe- 40 supporting jack, mechanism for automatically actuating the hammer and jack to impart to the jack and hammer relative longitudinal movements and means under the control of the operator to stop the relative longitudinal movements of the jack and hammer at any desired point, substantially as described.

In testimony whereof I affix my signature in presence of two witnesses.

ERASTUS E. WINKLEY.
